(57) **CLAIM**

The ornamental design for a curved dog bone shaped carabiner, as shown and described.

DESCRIPTION

FIG. 1 is a top plan view of a first embodiment of my new design for a curved dog bone shaped carabiner, the bottom plan view being a mirror image thereof;

FIG. 2 is a front plan view of FIG. 1.

FIG. 3 is a rear side plan view of FIG. 1.

FIG. 4 is a right side plan view of FIG. 1.

FIG. 5 is a left side plan view of FIG. 1.

FIG. 6 is a top perspective view of FIG. 1.

FIG. 7 is a top or bottom plan view, which are mirror images, of a second embodiment of my new design for a curved dog bone shaped carabiner.

FIG. 8 is a front plan view of FIG. 7.

FIG. 9 is a rear side plan view of FIG. 7.

FIG. 10 is a right side plan view of FIG. 7.

FIG. 11 is a left side plan view of FIG. 7; and,

FIG. 12 is a top perspective view of FIG. 7.
